UNITED STATES PATENT OFFICE.

DANIEL T. SPRING AND SAMUEL E. SPRING, OF WHEELING, WEST VIRGINIA, AS
SIGNORS OF TWO-THIRDS TO HENRY D. SCOTT, OF WHEELING, WEST VIRGINIA.

SCRAPER FOR ROLLED PLATES.

Application filed August 10, 1926. Serial No. 128,498.

This invention relates to mechanism for removing scale and other foreign matter from metal plates as the latter enter the rolls of a rolling mill, and the principal object of the invention is to provide a simple scraper mechanism mounted upon the roll housings at the entrance side of the mill whereby adherent foreign matter is effectively removed from the metal plates.

Another object of the invention is the provision of a unitary scraping mechanism comprising a supporting plate, a scraper member, guides for the scraper member, and means for actuating the scraper member, all mounted on the supporting plate, the latter being secured to the roll housings in adjusted relation to the entrance passage.

A further object of the invention is the provision of guides for the scraper member, these guides being laterally movable with relation to the inlet opening of the housing so as not to interfere with the work as the latter enter into the rolls.

Other objects and purposes will become apparent as the description of the invention proceeds. For a complete understanding of the invention, reference is to be had to the accompanying drawings forming a part of this specification.

In the drawings—

Figure 1 is a side view of the roll housing with the scraping mechanism mounted thereon;

Figure 2 is an enlarged front elevation of the scraper mechanism;

Figure 3 is a sectional view on line 3—3, Fig. 2;

Figure 4 is a sectional view on line 4—4, Fig. 2;

Figure 5 is a sectional view on line 5—5, Fig. 2; and—

Figure 6 is a detail sectional view showing the slotted link connection between the scraper plate and the actuating lever.

Referring to said drawings, reference character R designates generally a roll housing forming a part of a mill with which is associated the improved scraping mechanism of the present invention, which latter is designated generally by the reference character S. In Fig. 1 a plate P is shown entering the mill and as being acted upon by the scraping mechanism S, said plate being supported by conveyor rolls C.

A supporting plate 11 having inwardly extending side pieces 12 suitably spaced from the ends thereof is attached to the roller housing R by means of angle brackets 13, as is clearly shown in Fig. 3. The supporting plate 11 has outwardly extending vertical ribs 14 forming side guides for a scraper plate 16, which has removably mounted on its lower end, as by means of bolts 18, a scraper bar or blade 17. The upper end of said scraper plate 16 has attached thereto a longitudinally slotted link 19 which has connection with an actuating lever 20 that is pivoted upon the plate 11 at 21. It will here be noted that the scraper plate 16 is movable with relation to the lever 20 by reason of the slotted link connection just described, and it will also be noted that the link 19 is pivotally secured to the scraper plate 16 at 22 to permit the required relative movements of the actuating lever 20 and scraper plate. The connection between the link 19 and the lever 20 is shown in detail in Fig. 6, and it will there be seen that a headed bolt 23 carried by said lever 20 has a reduced threaded extension 23^a passing through the slot 26 in the link 19, and that a nut 27 secures the parts against displacement.

Located in front of the upper part of the scraper plate 16 is a horizontally disposed bar 28 secured at its ends to the plate 11, as by bolts 29. Said bar has in its rear face recesses 30 in which are received vertically movable guides 31 and 31^a which in their normal position have their lower end portions occupying a level below the path of travel of sheets to the rolls of the mill, and the lower inner sides of which are provided with removable wear plates 32 and 32^a, respectively. The upper end of the guide 31^a is slotted, as at 33, and is connected to the lever 20 through the intermediary of a slotted link 35, the latter being rigidly attached to the lever 20 by means of bolts 36. A pivot bolt 34 attaches said guide 31^a to said link 35, being directed through the slot 33 and a horizontal slot 35^a provided in a crosshead portion of said link. Said slotted link connection permits the guide 31^a to move laterally and vertically for a purpose which will hereinafter be described. The guide 31 has a slotted upper end 37 connected by a bolt 38 to one end of a longitudinally slotted lever 39 which is pivoted to the plate 11 at 40 and which has 110

its opposite end connected, as at 42, to an end of a link 41 which has its opposite end connected by a bolt 43 to a horizontally slotted link 44 secured to the lever 20. The lever 20 may be actuated by any suitable means, as by a solenoid 46, and carries a counterweight W on its opposite end. The described connections between the guides 31 and 31^a and the lever 20 provide for elevation of said guides when said lever 20 is moved in a counter-clockwise direction about its pivot 21 and for lowering said guides upon clockwise movement, as when the solenoid 46 is energized.

It is advantageous to provide for the movement of the guides 31 and 31^a outwardly relative to the path of travel of sheets entering the mill so that no interference is offered by the guides to the plate as the forward end of the latter passes between said guides. To this end the guides 31 and 31^a are arranged to be moved laterally during their upward movement. As shown by Fig. 5, the guides 31 and 31^a may move laterally in the recesses 30. Their upper ends may move laterally by reason of the slotted link connection hereinbefore described. To permit lateral movement of their lower ends the guides 31 and 31^a have their outer edges inclined, as shown at 47 and 48, respectively. Rollers 49 mounted in slotted holders 50 serve as anti-friction abutments for the outer edges of said guides 31 and 31^a. Said holders 50 are secured to the plate 11 by bolts 51, as shown in Fig. 2, the slots thereof providing for adjustment. The guides 31 and 31^a are provided with attached vertical rods 52 and 53, respectively, and on these rods are adapted to ride rollers 54 and 55 which are yieldably held thereagainst by springs 56 secured to eye bolts 57, the latter being mounted in the plate 11. Pivoted rods 58 and 59 suspend the rollers 54 and 55 from the cross strip 28. It will thus be seen that as the lever 20 is moved in a counter-clockwise direction about the pivot 21 to move the scraper plate 16 upwardly, the guides 31 and 31^a are likewise moved upward and, at the same time, are actuated to move laterally outward in opposite directions because of the tapered portions 47 and 48, the springs 56 causing the upper parts of the guides 31 and 31^a to follow the lateral movement of the lower parts 47 and 48 thereof.

From the foregoing description the construction, operation and advantages of the novel mechanism will be readily understood. As the forward end of the plate P approaches the rolls of the roll housing, the scraper mechanism and guides are withdrawn from the path of travel thereof. Having passed by said elements, the latter are actuated through the lever 20 to resume their normal positions, as shown in Fig. 2,

for effecting guiding and scraping of the plate.

While we have shown and described the preferred construction, it will be understood that certain changes in construction and arrangement of parts may be made without departing from the invention as defined by the appended claims.

What is claimed is—

1. The combination with a set of rolls and a roll housing, of a scraper device positioned in front of said housing, said scraper device comprising a scraper member, guides for said scraper member, and means for moving said guides laterally of the path of travel of sheets as the latter enter the rolls.

2. In combination with a set of rolls and a roll housing, a supporting plate attached to said housing, a sheet scraper movably mounted on said plate, guides for said scraper, a lever supported on said plate and connected to said scraper and said guides for operating the latter, and means for moving said guides laterally of the path of travel of sheets entering the rolls.

3. The combination with a roll housing, of a scraper device mounted on said housing, said device comprising a scraper plate, guides for said plate, and means for elevating said scraper plate and said guides.

4. A scraper apparatus comprising a scraper, vertically and laterally movable guides for said scraper, a lever for elevating and lowering said guides and said scraper, and slotted link connections between said lever and said scraper and guides whereby said scraper and guides may be moved upwardly without being moved laterally by said lever.

5. A scraper apparatus comprising a supporting plate, a scraper, guides for said scraper, an actuating lever pivotally connected to said plate, and connections between said guides and said lever on opposite sides of said pivotal connection of the lever of the plate, said connections comprising means whereby movement of said actuating lever will actuate movement of both of said guides in the same direction.

6. A scraper apparatus comprising a supporting plate, a scraper, and guides for the scraper, said guides being movable vertically and laterally, means normally maintaining said guides in guiding positions, and means for shifting said guides from said positions upon elevation thereof.

7. A scraper apparatus comprising a supporting plate, a scraper, movable guides for said scraper, said guides having tapered portions whereby longitudinal movement of said guides permits lateral movement thereof, means biasing said guides laterally away from each other, and anti-friction abutments for said guides.

8. A scraper apparatus comprising a

scraper, guides for said scraper, means for moving said scraper in one direction, means for moving said guides in the same direction, and means operable upon movement of 5 said guides in one direction to move said guides away from each other.

9. In a scraper apparatus, a scraper, and guides for said scraper movable therewith, each of said guides having a tapered portion, and a rod connected to said guide and spaced therefrom, a roller adapted to abut said tapered portion, and a spring tensioned 10 roller bearing on said rod whereby move-

ment of said guide in one direction causes its movement in a lateral direction. 15

10. The combination with a roll housing, of a scraper device comprising a scraper plate, guides for said scraper plate, means for simultaneously moving said scraper plate and said guides in either of two vertical directions, and means for moving said guides laterally relative to each other. 20

In testimony whereof we affix our signatures.
